ATTORNEYS

UNITED STATES PATENT OFFICE.

PATRICK F. McNULTY, OF NEW YORK, N. Y.

SHOE CONSTRUCTION.

Application filed September 25, 1920. Serial No. 412,670.

To all whom it may concern:

Be it known that I, PATRICK F. McNULTY, a citizen of the United States, and a resident of the city of New York, borough of 5 Manhattan, in the county and State of New York, have invented a new and Improved Shoe Construction, of which the following is a full, clear, and exact description.

This invention relates to foot wear and 10 has particular reference to an improvement in the construction of shoes. The invention contemplates the provision of a shoe, scientifically constructed to effect the proper and natural growth of the foot of the wearer, 15 and which functions to correct and cure defective and unnatural developments of the feet, occasioned by various causes.

Another object of the invention is to provide a shoe having the shank portion of the 20 sole constructed in such a manner as to properly and efficiently support the arch of the foot, to prevent or cure trouble resulting from the lack of proper support of the bones at this point.

25 A further object of the invention is to provide a shoe which functions to properly balance and arrange the points of contact of the foot whereby the weight of a person will be properly distributed on said points 30 of contact.

35 A still further object of the invention is to provide a shoe provided with means for separating the great toe from the next adjacent toe in order to prevent cramping of the digits and malformation of the same.

With the above recited and other objects in view, some of which will be more apparent hereafter, reference is had to the following detailed description, the appended 40 claims and the accompanying drawings forming a part of this application, and in which;

45 Figure 1 is a perspective view of a shoe constructed in accordance with the invention.

Figure 2 is a horizontal sectional view through the lower portion of the upper taken approximately on the line 2—2 of Figure 1.

50 Figure 3 is a transverse sectional view taken on the lines 3—3 of Figures 1 and 2.

Figure 4 is a longitudinal sectional view on the line 4—4 of Figure 2.

Figure 5 is a transverse sectional view on the line 5—5 of Figure 2.

Figure 6 is a transverse sectional view 55 taken on the line 6—6 of Figure 2.

Referring to the drawings by characters of reference, 10 and 11 designate the outer and inner sections of an upper which are secured together at the back as at 12 and at 60 the forward portion by the stitching 13 which runs from the toe to the vamp. The upper sections are stitched adjacent their lower edges to the insole 14 to provide the flanges 15 beyond the point of connection of 65 the upper to the insole. In order to provide means for separating the great toe from the next adjacent toe, a partition is provided, consisting of a strip of leather 16 bent upon itself and secured at the folded portion by the stitching 13 to the upper. The 70 opposite free ends 17 of said strip are passed through a slit 18 in the insole and laterally bent and secured thereto as illustrated in Figure 3 of the drawings. The strip 16 is 75 disposed at an angle to the longitudinal center line of the shoe to provide an enlarged entering mouth to admit of the ready insertion of the great toe when drawing the shoe in place on the foot. The tread member generally designated by numeral 19 is preferably constructed of felt or any other suitable material which is provided adjacent its rear end with a heel 20, the upper portion of 80 which is depressed as at 21 to accommodate 85 the heel of the foot. The heel portion of the tread member is connected to the front or sole portion 21^a by means of a shank 22, the lower surface of the center portion 23 of 90 which is in alignment with the lower surface of the heel and front portion 20 and 21. The front or sole portion 21^a is provided with the depressions 24, 25 and 26, the former being 95 adapted to accommodate the ball of the foot lying directly in rear of the great toe, the depression 25 being adapted to accommodate the ball of the foot lying directly in rear of the small toe and the latter depression 26 being designed to accommodate the portion of the big toe which contacts with the insole. In constructing the shoe the insole 14 is constructed to conform to the upper surface of the tread member 19. By 100 this arrangement it will be observed that the shank will properly support the arch of the foot to prevent the ordinary troubles such as broken or fallen arches. In practice, an outer covering sole 27 is provided as a tread

surface to prevent wear on the felt sole and the sole 19 and outer covering sole 27 are secured to the upper by the stitching 28 which passes through the flanges 15 as clearly illustrated in the drawings.

In using the shoe, the strip 16 together with the upper will function to properly position the major points of contact of the foot in their respective depressions to insure an even bearing and support of the weight of the person. It will be observed from Figure 4 of the drawings that the thickness of the tread member 19 is reduced at the juncture of the front portion of the shank 22 with the sole portion 21^a thereof from the depressions 24 and 25 to the toe of the same, in order that the bend in the foot will occur at the proper place during the operation of walking. The construction of the bottom surface of the tread member 19 effects a contact of the same with the ground throughout its length to properly support the arch as well as the heel and front portion or sole of the foot.

While there has been illustrated and described a single and preferred embodiment of the invention, it is to be understood that the right is reserved to embodiments other than those actually illustrated herein to the full extent indicated by the general meaning of the terms in which the claims are expressed and by variations in the phraseology of the same.

Having thus described my invention, I claim as new and desire to secure by Letters Patent;

1. A shoe embodying an upper and a tread

member attached thereto, the latter constructed from a piece of material having inwardly and downwardly inclined cutaway portions extending inwardly from the opposite sides thereof to provide a heel, shank and sole, said shank having the central portion of its under side disposed in the same plane with the under side of the sole and heel, the upper surface of said tread member having depressions therein and elevations thereon conforming to the natural configuration of the under side of the foot to promote the proper growth thereof and articulation of the bones, and facing strips covering the upper and under surface of said tread member and conforming to the configuration thereof.

2. A shoe embodying an upper and a tread member attached thereto, the latter constructed from a piece of resilient material having inwardly and downwardly inclined cutaway portions extending inwardly from the opposite sides thereof to provide a heel, shank and sole, said shank having the central portion of its under side disposed in the same plane with the under side of the sole and heel, the upper surface of said tread member having depressions therein and elevations thereon conforming to the natural configuration of the under side of the foot to promote the proper growth thereof and articulation of the bones, and facing strips covering the upper and under surface of said tread member and conforming to the configuration thereof.

PATRICK F. McNULTY.
